UNITED STATES PATENT OFFICE.

ERNST J. BERG, OF SCHENECTADY, NEW YORK, ASSIGNOR TO GENERAL ELECTRIC COMPANY, A CORPORATION OF NEW YORK.

LIGHTNING-ARRESTER.

No. 863,773.

Specification of Letters Patent.

Patented Aug. 20, 1907.

Application filed January 8, 1907. Serial No. 861,835.

To all whom it may concern:

Be it known that I, ERNST J. BERG, a citizen of the United States, residing at Schenectady, in the county of Schenectady and State of New York, have invented 5 certain new and useful Improvements in Lightning-Arresters, of which the following is a specification.

My present invention relates to lightning arresters adapted for use on electric systems and more particularly direct-current circuits.

- 10 It comprises an arrangement of condensers of ordinary type or electrolytic line for relieving the conductors from high frequency oscillations; it also comprises a spark gap and other elements for relieving the line from disturbances of a lower frequency.
- 15 The arrangement of the apparatus will be understood by reference to the accompanying drawing forming a part of this specification.

The drawing shows my invention as applied to a direct-current system of about 600 volts. The line conductor 1 is connected to the translating device 2 through an impedance such as the reactance coil 3. I have shown the translating device 2 as consisting of a single motor such as a street car motor; but the drawing is only diagrammatic and the translating device 25 may consist of a group of motors, or as is common, of the entire equipment of a single car. Two condensers 4 and 5 are placed in series across reactance 3, and have their common armatures connected to ground through a conductor 6. These condensers serve the 30 purpose of permitting a free path for any high frequency-high voltage oscillations and thereby reduce the potential gradient in the motor winding. This same result is obtained by the reactance although for a different reason. The reactance causes a partial reflection point for the high voltage usage and therefore reduces the maximum value on the motor winding. Obviously the condenser should contain as low inductive reactance as possible and the reactance as little

capacity between turns as possible. A second path to ground from conductor 1 includes a spark gap 7 with a 40 blow-out magnet 8 arranged so that a direct and heavy discharge of energy may take place from the line conductor to ground without passing through either of the condensers or through reactance 3.

With the arrangement above described, the relatively infrequent discharges of low frequency pass across spark gaps 7 and thence to ground, while the more common oscillation disturbances induced by switching, short circuits, etc. pass readily through the condensers without breaking down the spark gap 7. 50 and without giving the line current any possible opportunity for following through on the high potential discharge.

What I claim as new and desire to secure by Letters Patent of the United States, is,

- 55 1. A lightning arrester comprising a reactance, condensers in parallel therewith, a ground connection for said condensers, and a separate discharge path to ground through a spark gap.
2. The combination with a line conductor, a reactance 60 connected therewith, condensers in parallel with said reactance, and a grounded spark gap path in parallel with one of said condensers.
3. The combination of a line conductor, a translating device electrically connected therewith through a reactance, condensers connected in series across said reactance and forming a discharge path for high frequency oscillations, and a discharge path including a spark-gap connected to said line conductor. 65
4. The combination with a line conductor, a translating device connected therewith through an impedance, reactive means connected across said impedance and having a ground connection, and a discharge path in parallel with one of said reactive means.

In witness whereof, I have hereunto set my hand this 75 7th day of January, 1907.

ERNST J. BERG.
